UNITED STATES PATENT OFFICE.

ANKER PETERSEN, OF WINTHROP, MASSACHUSETTS.

WARP LEVER FOR BRAIDING MACHINES.

Application filed August 16, 1922, Serial No. 532,161.

To all whom it may concern:

Be it known that I, ANKER PETERSEN, a citizen of the United States of America, and resident of Winthrop, in the county of Suffolk and State of Massachusetts, have invented new and useful Improvements in Warp Levers for Braiding Machines, of which the following is a specification.

This invention concerns circular braiding machines of that type having two series of bobbins mounted respectively upon rotary supports and revolving in opposite directions, and provided with oscillatory "warp levers" for causing the threads of one series to pass alternately over and under successive bobbins of the other series, and relates more particularly to the lever devices and associated parts.

The object of the invention is to provide an improved warp lever of light weight yet of sufficient strength to perform its intended function and which can be produced easily and at low cost, together with a guide for supporting such lever during its oscillatory movement so constructed and arranged as to oppose little resistance to the movement of the lever.

Fig. 1 is a fragmentary plan view of a braiding machine of that type in which two series of thread carriers are revolved in opposite directions, and showing the warp thread lever and guide member of the present invention as applied thereto;

Fig. 2 is a fragmentary sectional view on a line such as 2-2 of Fig. 1;

Fig. 3 is a fragmentary sectional view on the line 3-3 of Fig. 1; and

Fig. 4 is a vertical cross section on a line such as 4-4 of Fig. 2 to smaller scale and omitting the thread lever and associated parts.

Referring to the drawings the numeral 1 indicates the rotating support upon which the outer or warp series of thread carriers is mounted. The relatively stationary cam cylinder 2 is arranged concentrically with the member 1 and is provided with a cam slot or groove having portions such as 3^a substantially parallel with and adjacent to the lower edge of the cam member 2, other portions 3^b substantially parallel with and adjacent to the upper edge of the cam member, and inclined portions 3^c connecting the parts 3^a and 3^b, all in usual and well known manner. Projecting outwardly from the peripheral surface of the member 1 are a series of brackets 4, only one of these brackets being illustrated. Each of the brackets 4 is provided with a pivot pin 5 at its outer extremity upon which is pivotally secured one end of a warp thread lever 6. In accordance with the present invention, this lever is of blade-like form, being made from sheet material such as steel of substantially uniform thickness from end to end and preferably highly resilient. This lever is cylindrically curved on an arc concentric with the inner face of the cam member 2. The outer end of the lever 6 is provided with a thread guiding element, shown as an open notch 7, and at a point substantially midway of its length an outstanding pivot pin 8 is fixed. A cam follower 9 of suitable configuration is pivotally mounted upon the pin 8, a washer 10 preferably being interposed between the outer surface of blade or lever 6 and the inner wall of the member 2. The lever blade 6 is slotted longitudinally as indicated at 11 between its free extremity and a point adjacent to the cam follower. A bracket 12 is secured by means of screws 13 to the peripheral surface of the member 1 and has an outstanding part 14 which is elongate in a vertical direction and is provided with an outer arcuate face 15. A series of plugs 16 of some absorbent material, as for example wood, are secured in openings in the member 14 and the ends of these plugs project slightly beyond the face 15 and collectively constituting a guide surface of curved contour. This guide surface as indicated in Figs. 1 and 2, engages the lever blade 6 at a point between the fulcrum 5 thereof and the cam follower 9. The plugs 16 are preferably soaked with oil or other suitable lubricating medium before insertion in the member 14 and may, if desired, be supplied with additional oil from time to time as is necessary. A thread guiding finger 17 is preferably secured in the head of the pivot pin 15 and serves to guide the thread on its way from the bobbin to the notch 7.

In the operation of the device, the member 1 rotates, carrying with it the bracket 4 and the bracket 12. The lever blade 6 is thus moved bodily with respect to the cam member 2 as the follower 9 travels along the cam groove thereby imparting an up-and-down oscillating movement to the blade 6. This movement of the blade causes the yarn which engages the notch 7 to travel

up and down as is necessary in machines of this character for passing it alternately above and below the thread carriers of the inner series. As the cam follower is set at an intermediate point in the curved lever, the cam follower must describe a surface of substantially spherical curvature and in order that the follower may fit snugly in the cam groove at all times the inclined portions 3^c of the groove are deeper at points intermediate their lengths than are the portions 3^a and 3^b of the groove, as indicated in Fig. 4 wherein such difference in depth is somewhat exaggerated for purposes of illustration. The surface of the blade 6 which engages the antifriction members 16, also describes a spherical surface so that it is thus necessary that the engaging faces of the members 16 collectively form a surface curved in a vertical plane, as indicated in Fig. 3.

In warp levers as heretofore constructed it has commonly been attempted to secure the desired resiliency by securing a flexible member carrying the thread guide to a relatively rigid part having a pivotal bearing for the lever. With such arrangements it is exceedingly difficult to temper the resiliency part after its attachment to the rigid member or properly to secure it to the latter, if previously tempered. In accordance with the present invention the lever may be made by a stamping operation, thus reducing the cost to a minimum and permitting the tempering of the lever as a whole. The lever thus formed is highly resiliency and provides the necessary tension upon the yarn at all times, the slot 11 serving to increase the resiliency of the outer end of the lever. In order to avoid detracting from the resiliency of the lever so far as possible, while at the same time reducing the friction between it and the guide to a minimum, the guide member is disposed at a point between the cam follower and the fulcrum. As thus arranged, the guide member furnishes the necessary support to the lever requisite to prevent the cam follower from being dislodged from its groove as the lever is flexed under varying yarn tension, but without cramping the latter or preventing its free bending under unusual tension to which the thread may be subjected. At the same time by the use of the oil absorbent members 16 constituting the wear surface of the guide member, it is possible to reduce friction to a minimum and to increase the life of the levers very materially.

60 What I claim and desire to secure by Letters Patent of the United States is:

1. A warp lever for use in a circular braiding machine comprising an integral elongate resilient blade of substantially uniform thickness from end to end fulcrumed

adjacent to one end and having a thread guiding opening at its opposite end, said blade being cylindrically curved from end to end concentrically with the axis of the machine. 70

2. A warp lever for braiding machines comprising an integral elongate cylindrically curved resilient blade of substantially uniform thickness from end to end, pivotal supporting means at one end of the blade, a thread guide at the opposite end of said blade, means intermediate the ends of said blade for engagement with actuating means, and guide means engaging the blade intermediate its ends. 75

3. A warp lever for use in a circular braiding machine comprising an integral elongate resilient steel blade having a thread guiding notch in one end and a pivotal support adjacent to the other, and a cam engaging member secured to said blade at a point intermediate said notch and support, said blade being curved from end to end on an arc concentric with the axis of the machine. 80

4. A warp lever for braiding machines comprising an integral elongate blade of resilient material having a thread guiding notch at one end, said blade being cylindrically curved from end to end, a pivotal support at the other end, and a cam engaging element at a point substantially midway of its length, said blade being more flexible at that portion lying between the notched end and said cam engaging element than between the latter and the pivotal support. 95

5. A warp lever for a circular braiding machine comprising an integral elongate blade of resilient material and of substantially uniform thickness from end to end having a thread guide at one end and pivotal supporting means at the other, said blade being curved from end to end on an arc concentric with the axis of the machine, and a cam engaging element secured to the blade at a point adjacent its longitudinal center, said blade having an elongate opening extending substantially from its free end to said cam engaging element. 105 110

6. In combination in a braiding machine a warp lever comprising an elongate element pivotally supported adjacent to one end and having a thread guide at the other, a cam follower secured to said element at a point adjacent to its center, and a relatively fixed guide having an antifriction surface engaging said element at a point intermediate said cam follower and the pivotal support for said element. 120 125

7. In combination in a braiding machine, an oscillatory warp lever comprising an elongate resilient blade pivotally supported adjacent to one end and having a thread guide at the other, a cam follower secured 130

- to said blade adjacent to its longitudinal center, and a fixed guide having a series of lubricating plugs collectively constituting a surface engaging said blade at a point 5 between said cam follower and its fulcrum throughout its entire arc of movement.
8. In combination in a braiding machine a warp lever comprising a flexible blade having a thread engaging notch at one end, 10 a pivotal support at its opposite end, and a cam engaging element adjacent to its center, and a guide member fixed relatively to said blade and having a surface engaging said blade at a point between said cam 15 engaging element and the pivotal support.
9. In combination in a braiding machine a warp lever comprising a curved resilient blade pivotally supported adjacent to one 20 end to swing about an axis lying in its plane of curvature, said blade having a thread guiding element at its free extremity and a cam follower at a point adjacent to its center, and a guide member having a blade
- engaging surface curved in a plane substantially perpendicular to the plane of 25 curvature of said blade and engageable with the blade at a point adjacent to said cam follower and between the latter and the pivotal support for the blade.
10. In combination in a braiding machine, 30 a curved warp lever of resilient material pivotally supported at one end to oscillate about an axis lying in its plane of curvature, a cam follower secured to said lever adjacent to its center of length, and 35 a relatively fixed guide having a plurality of oil absorbent plugs collectively providing a lever engaging surface curved in a plane perpendicular to that of the curvature of the lever, and engaging the latter 40 at a point adjacent to said cam follower and between the latter and the pivotal axis of the lever.

Signed by me at Boston, Massachusetts,
this ninth day of August, 1922.

ANKER PETERSEN.
